Attorney

UNITED STATES PATENT OFFICE.

JESSE BALDWIN, OF JEFFERSON BARRACKS, MISSOURI.

TOOL.

1,320,825.

Specification of Letters Patent.

Patented Nov. 4, 1919.

Application filed October 7, 1918. Serial No. 257,312.

To all whom it may concern:

Be it known that I, JESSE BALDWIN, a citizen of the United States, residing at Jefferson Barracks, in the county of St. Louis and 5 State of Missouri, have invented certain new and useful Improvements in Tools, of which the following is a specification, reference being had to the accompanying drawings.

- 10 This invention relates to tools, and has for its primary object to provide a very simply constructed and serviceable tool which may be adapted to a multiplicity of different uses.
- 15 It is one of the particular objects of the present invention to provide an improved mounting and arrangement of a screwdriver upon a hammer-head, whereby the screwdriver may be readily moved to an operative or inoperative position with respect to the hammer-head, the hammer-head and the handle being recessed in one side to receive a screwdriver in the inoperative position thereof, so that the screwdriver will serve as 20 a reinforcement for the handle and minimize the possibility of breakage or fracture of the handle.

It is also another object of the invention to provide simple and effective means for 30 positively and securely fastening the hammer-head upon the handle.

It is also an additional object of the invention to provide a tool of the above character, the head of which is provided with 35 tack- and nail-extracting means, wire-stretching means, and a tack-receiving pocket or recess in the end face of the hammer-head with a suitable closure therefor.

With the above and other objects in view, 40 the invention consists in the improved construction, combination, and relative arrangement of the several parts as will be hereinafter more fully described, subsequently claimed, and illustrated in the accompanying drawing, in which similar reference characters designate corresponding parts throughout the several views, and 45 wherein:—

Figure 1 is a side elevation of my improved tool showing the screwdriver in its extended or operative position;

Fig. 2 is a longitudinal section, with the screwdriver in its folded, inoperative position;

55 Fig. 3 is a section taken on the line 3—3 of Fig. 1; and

Fig. 4 is an end elevation of the hammer-head, showing the cover for the tack-receiving recess partly withdrawn.

Referring in detail to the drawing, 5 60 designates the head of the tool, which may be of any desired dimensions and is formed upon one of its ends with a hammer enlargement 6. The other end of the head 5 is elongated and provided with a flat or plane 65 end face 7, which is preferably highly polished. At one end of the face 7, the head 5 is formed with the spaced claws 8, the inner opposed edges of which are divergently disposed and preferably beveled. 70 These claws are employed for the extraction of tacks, the head of the tack being received in the recess between the beveled edges thereof. At the opposite end of the face 7 of the tool head, the relatively long claws 9 75 are formed, the inner edges of which are likewise beveled and divergently disposed. These claws 9 preferably curve slightly inwardly toward the body of the head and are employed for the extraction of nails. 80

The head 5 is centrally formed with a handle-receiving socket or opening 10, in which the reduced end of a handle 11 is fitted. This end of the handle is provided with a transverse opening to coincide with 85 a similar opening in the head 5. Through these registering openings, a fastening bolt 12 is disposed. A flexible metal band 13 has an opening in one end to receive said bolt, said end of the band being disposed between the bolt head and the side of the tool head. The band is then extended around the end of the tool head 5 and the other end of said band, which is likewise provided with an opening, is engaged over the 90 threaded end of the bolt 12. The nut 14 is then threaded upon the bolt to tightly clamp the latter end of the band against the opposite side of the tool head.

The tool head 5 is formed in one of its 100 side faces with a groove or channel 15, which extends at right angles to the longitudinal axis of said head, and said channel is in alinement with a longitudinally extending groove or channel 16 formed in the corresponding side of the handle 11. A pin 17 extends across the outer end of the channel 15 and is securely fixed in the tool head. Upon this pin, a screw-driving bit 18 is loosely engaged at one of its ends for pivotal or swinging movement. Thus, the bit 18 may be extended from the end of the tool 105 110

head, as seen in Fig. 1, so that its point can be operatively engaged with the kerf in the screw head and said screwdriver then operated by turning the tool handle and the 5 head 5 fixed thereto. To the tool head, at one side of the channel 15 therein, resilient retaining clips 19 are pivoted at one of their ends, as at 20, and are adapted to be sprung outwardly and then moved upon the screw- 10 driver bit 18 when the latter is folded in its inoperative position, as seen in Fig. 2. In this position of the screwdriver, the free end thereof fits within the channel or groove 16 in the tool handle 11. The handle of the tool 15 is thus somewhat strengthened or reinforced at its point of connection to the tool head and liability of breakage or fracture of the handle at its junction with the head is thus reduced.

20 In the end face 7 of the tool head, centrally thereof, a pocket or recess 21 is formed, in which a number of tacks may be conveniently carried. The open side of this pocket is adapted to be closed by a 25 slide plate 22, which is mounted in transverse guide grooves or channels formed in the face of the tool head. When the slide plate or cover is forced inwardly and over the open side of the pocket 21, said plate 30 is flush with the face 7 of the tool head, so that this end of the head will present a perfectly smooth, flat surface, which may be moved over a board, floor or other part when it is desired to extract nails or tacks.

35 In the inner edge of the tool head, between the handle and the extracting claws 9, a notch or recess 23 is formed. This recess is adapted to receive a fence wire, the tool being engaged with the wire immediately behind one of the barbs thereof. Thus, by means of the tool, the wire can be conveniently stretched.

In the butt end of the handle 11, a rectangular longitudinally extending bore 24 45 is formed to receive a steel rule 25. This rule may be of any suitable length and is properly graduated. The rule is entirely received within said bore, and the end face of the handle is preferably notched at opposite sides of the bore 24 so that the fingers 50 may be readily engaged with the end of the rule and the latter withdrawn.

From the foregoing description, taken in connection with the accompanying drawing, the construction, manner of use and several advantages of my invention will be clearly and fully understood. It will be seen that I have devised a very convenient and serviceable tool, and one which can be 55 applied to a variety of uses. The several parts of the device are of simple and durable construction, so that the tool as a

whole may be cheaply manufactured and sold.

While I have herein shown and described 65 the preferred construction and relative arrangement of the several parts of my improved tool, it is to be understood that the same are susceptible of considerable modification and I, therefore, reserve the privilege of adopting all such legitimate changes 70 as may be fairly embodied within the spirit and scope of the invention as claimed.

I claim:—

1. In a tool of the character described, 75 a tool head and handle therefor, said handle and the head having alined channels formed in their corresponding outside faces, a screwdriver disposed entirely in said channels in the inoperative position thereof 80 and adapted to be extended from the channels in projecting relation to the tool head, and means for retaining the screwdriver within said channels.

2. In a tool of the character described, 85 a tool head and handle therefor, said handle and the head having alined channels formed in their corresponding outside faces, a screwdriver pivotally mounted at one end in the channel in the tool head and adapted to be 90 folded into said channel and the channel in the handle in the inoperative position of the screwdriver, and means for retaining the screwdriver within said channels and projected from the head.

95 3. In a tool of the character described, a tool head and handle therefor, said handle and the head having alined channels formed in their corresponding side faces, a screwdriver pivotally mounted at one end in 100 the channel in the tool head and adapted to be folded into said channel and the channel in the handle in the inoperative position of the screwdriver, and resilient retainers pivotally mounted upon the side of the tool 105 head to engage the screwdriver and retain the same within said channels.

4. A tool having a longitudinally extending channel formed in one side face thereof, the channel being open at one end, and a 110 screwdriver pivotally mounted at one end in said channel and adapted to be folded into said channel in the inoperative position of the screwdriver but rotated upon its pivot to a projected position, and retaining devices 115 pivotally mounted upon the side of said tool to engage over the screwdriver and retain the same within the channel.

In testimony whereof I hereunto affix my signature in the presence of two witnesses. 120
JESSE BALDWIN.
